[57] ABSTRACT

An ironing apparatus which compactly and unitarily comprises an iron, an ironing board, support structures for said iron and said ironing board, a casing of relatively small volume for containing the same with frame means fixing said casing to said support structures whereby said apparatus is adapted for operative disposition when said casing is opened to provide a base with said ironing board being in extended condition and said iron disposed thereabove, and inoperative position wherein said apparatus components are fully received within the closed casing for ready transportability.

FIG. 6

This technical drawing illustrates a height-adjustable chair mechanism. A central vertical support 183 is connected to a horizontal base 10. A side support arm 40 is attached to the vertical support 183 and the base 10. The side support arm 40 includes a seat 96 and a backrest 54. A central support 184 is also shown. Various components are labeled with numbers: 180, 175, 148, 138, 143, 141, 140, 137, 184, 102, 101, 18, 17, 14, 8, 7, 10, 4, 96, 64, 54, 54', 44, 19, 13, 46, 5, and 3. The drawing shows the chair in an upright position on the left and a folded or partially assembled state on the right.

IRONING APPARATUS

BACKGROUND AND SUMMARY OF THE INVENTION

This invention relates in general to ironing equipment and, more particularly, to a self-contained ironing apparatus embodying an iron, ironing board, and casing which are connected into integral structure.

Heretofore numerous efforts have been made in the art to develop ironing apparatuses for either providing a foldable or extensible ironing board or articulating support linkage for an iron so that either of the same may be stored within a relatively reduced volume. However, there has not been provided an effective unit which integrally contains an ironing board and iron with support structure therefor together with a permanently engaged casing since the space problems presented have been considered insurmountable from the standpoint of achieving a desired compactness. Thus, to the present time the average housewife has necessarily had to accept the necessity of storing an ironing board and iron independently with the inherent requirement of appropriate storage space and multiple handling.

Therefore, it is an object of the present invention to provide an ironing apparatus which unitarily comprises an iron, ironing board, carrying or storage casing therefor with means physically integrating the same.

It is another object of the present invention to provide an ironing apparatus of the type stated wherein the ironing board, when extended, is of full conventional size but which is adapted for collapsing into minimal form; there being means for readily moving said board into and from operative condition.

It is another object of the present invention to provide an ironing apparatus of the type stated wherein the casing when in opened condition serves to stabilize the ironing apparatus in operative condition so as to be functional in either aspect of its usage.

It is a further object of the present invention to provide an ironing apparatus of the type stated which embodies a unique support linkage for the iron so as to present same above the board in operative position and to permit of collapsing for snug reception within the casing when closed; said linkage being easily disposed in operative, iron-supporting condition and as easily returned to collapsed condition so that the operator is occasioned no physical hardship in usage.

It is a still further object of the present invention to provide an ironing apparatus of the type stated wherein the casing is of relatively small volume, so as to be easily carried by an individual as well as to require but limited space in storage.

It is a still further object of the present invention to provide an ironing apparatus of the type stated which incorporates unique means for maintaining the components in operative condition to avoid any inadvertent, accidental premature collapsing and with such means being easily manipulated by the user so that when desired the said components may be disposed for return to collapsed, stored condition within the casing.

It is another object of the present invention to provide an ironing apparatus of the type stated which permits of the user remaining in a seated condition for effecting movement of the components into operative

condition, for ironing usage, and for restoration of the components into casing-received condition so that a user of limited strength or advanced years could utilize the ironing apparatus with physical ease and effectiveness.

It is another object of the present invention to provide an ironing apparatus of the type stated which is of relatively simple construction having a minimum of parts fabricated from durable materials so as to render said apparatus resistant to breakdown; which is economical in production; which is extremely reliable in usage; and the usage of which eliminates the heretofore accepted inconveniences associated with storing of ironing boards and ironers.

It is a still further object of the present invention to provide an ironing apparatus of the type stated which will permit of the usage of any selected type of iron, such as the dry or steam types; and the operation of which requires only connection to the customary wall socket.

BRIEF DESCRIPTION OF THE DRAWINGS

FIG. 1 is a perspective view of the fully closed casing of an ironing apparatus constructed in accordance with and embodying the present invention.

FIG. 2 is a perspective view of the casing in opened condition illustrating the operative components of the ironing apparatus in full contracted, inoperative condition.

FIG. 3 is a perspective view of the ironing apparatus with the ironing board illustrated in operative condition and the iron with the associated linkage in stored or inoperative condition.

FIG. 4 is a fragmentary perspective view of the ironing board with one end section in upwardly swung condition.

FIG. 5 is a perspective view of the ironing apparatus in expanded, operative condition.

FIG. 6 is a fragmentary perspective view illustrating the iron in operative relation to the ironing board.

FIG. 7 is a vertical view taken on the line 7—7 of FIG. 3.

FIG. 8 is a vertical view, in partial section, taken on the line 8—8 of FIG. 3.

FIG. 9 is a vertical view taken substantially on the line 9—9 of FIG. 8 but illustrating the lever and associated leg in inoperative position.

FIG. 10 is a horizontal transverse sectional view taken on the line 10—10 of FIG. 8.

FIG. 11 is a fragmentary perspective view of the upper end portion of the ironing board support column and associated elements.

FIG. 12 is a bottom view of the ironing board taken on the line 12—12 of FIG. 3.

FIG. 13 is a vertical view taken on the line 13—13 of FIG. 12.

FIG. 14 is a vertical view taken substantially on the line 13—13 of FIG. 12 but illustrating the one end section in upwardly swung position.

FIG. 15 is a fragmentary view taken on the line 15—15 of FIG. 13.

FIG. 16 is a vertical view taken on the line 16—16 of FIG. 12, illustrating the latch mechanism of the ironing board corner portion in inoperative position.

FIG. 17 is a vertical view taken substantially on the line 16—16 of FIG. 12 but illustrating the latch arm in disengaged condition for releasing the corner portion to swing.

FIG. 18 is a vertical view taken substantially on the line 16—16 of FIG. 12 but illustrating the latch mechanism as the corner portion is being swung.

FIG. 19 is a vertical view taken on the line 19—19 of FIG. 3, illustrating the main support arm in downwardly swung inoperative position.

FIG. 20 is a vertical view taken substantially on the line 19—19 of FIG. 3 illustrating the main support arm in upwardly swung operative position.

FIG. 21 is a vertical front view taken on the line 21—21 of FIG. 19.

FIG. 22 is an enlarged fragmentary vertical view taken on the line 22—22 of FIG. 7 illustrating the main and intermediate support arms of the iron linkage in stored condition.

FIG. 23 is a fragmentary vertical view taken substantially on the line 22—22 of FIG. 7 but illustrating the main and intermediate support arms of the iron support linkage in extended or operative relationship.

FIG. 24 is a vertical view taken on the line 24—24 of FIG. 22.

FIG. 25 is an outer end elevational view of the iron lowering and raising mechanism with part of the casing removed.

FIG. 26 is a vertical sectional view taken on the line 26—26 of FIG. 25.

FIG. 27 is a vertical view taken on the line 27—27 of FIG. 25.

FIG. 28 is a wiring diagram of the control circuit for the iron raising and lowering mechanism.

FIG. 29 is an end view of the casing, in closed condition, of another form of ironing apparatus constructed in accordance with and embodying the present invention.

FIG. 30 is an elevational view of the end of the casing opposite to that illustrated in FIG. 29.

FIG. 31 is a perspective view illustrating the casing, in fragmented form, in opened condition with the operating components in contracted or inoperative condition; the ironing board being removed.

FIG. 32 is an end elevational view taken on the line 32—32 of FIG. 31.

FIG. 33 is an end elevational view taken on the line 33—33 of FIG. 31.

FIG. 34 is a perspective view of the ironing apparatus illustrating the ironing board support structure in operative condition; the ironing board being partially removed.

FIG. 35 is a perspective view illustrating the iron support linkage in extended condition.

FIG. 36 is a vertical view taken on the line 36—36 of FIG. 34.

FIG. 37 is a vertical, fragmentary view taken substantially on the line 36—36 but illustrating the control links with the casing in closed condition.

FIG. 38 is a horizontal view taken on the line 38—38 of FIG. 36.

FIG. 39 is a vertical view taken on the line 39—39 of FIG. 36.

FIG. 40 is a vertical transverse sectional view taken on the line 40—40 of FIG. 34.

FIG. 41 is an enlarged plan view of the portion of ironing board end section indicated at 41 in FIG. 34, illustrating the corner portion planarwise aligned with the adjacent end section.

FIG. 42 is an enlarged plan view of the portion of the ironing board indicated at 41 in FIG. 34 but illustrating the corner portion in folded or planarwise parallel relationship with the said adjacent end section.

FIG. 43 is a vertical transverse section taken on the line 43—43 of FIG. 41.

FIG. 44 is a vertical transverse sectional view taken on the line 44—44 of FIG. 34.

FIG. 45 is a vertical transverse sectional view taken substantially on the line 44—44 of FIG. 34 but illustrating the ironing board in lowered or inoperative condition.

FIG. 46 is a fragmentary top view taken on the line 46—46 of FIG. 45 but with portions of the board being broken away.

FIG. 47 is an enlarged fragmentary perspective view of the latch mechanism of the iron support linkage, illustrating same in latched condition.

FIG. 48 is a vertical transverse sectional view taken on the line 48—48 of FIG. 57.

DESCRIPTION OF THE PRACTICAL EMBODIMENTS

Referring now by reference characters to the drawings, A generally designates an ironing apparatus which unitarily comprises an ironing board b, a support structure therefor indicated broadly c, an iron d, support linkage for said iron l, a raising and lowering mechanism f for said iron and a casing k fixedly integrated with said components and dimensioned for snugly receiving same when in inoperative condition. As will be described hereinbelow, ironing apparatus A is thus a self-contained unit with the constituent elements uniquely adapted for interfitted, contracted disposition for full accommodation within casing k when the latter is closed and equally adapted for extension into operative condition with casing k serving as a stabilizing base and the iron presented for effective manipulation by the user when seated. Ironing apparatus A is so designed that casing k is of relatively small volume, having dimensions of approximately 5 1/2-inches in width, 14-inches in length, and 19-inches in height, and with the total apparatus having a weight of approximately 20 pounds so that when casing k is in closed condition with the apparatus components neatly and compactly stored therein the same may be easily transported by the average housewife.

Casing k comprises narrow parallel top and bottom walls 1,2, respectively, relatively wide side walls 3,4 and parallel end walls 5,5', said top wall 1 and end walls 5,5' are constituted of flanges 6,7 extended continuously throughout the adjacent edges of said side walls 3,4; said flange 6 being of relatively greater extent than flange 7. Each side wall 3,4 along its normally lower transverse edge is hingedly engaged to the adjacent side edge of bottom wall 2 as by pintles (not shown) received within cooperating knuckles 8 whereby said side walls are swingable upwardly toward each other into closed-casing condition (FIG. 1) and downwardly away from each other for flatwise disposition upon a support surface, such as a floor, (FIG. 2) for providing

a stabilizing base for apparatus A when in operative condition (FIGS. 2 and 3). The terminal margins of flanges 6,7 are aligned with the hinged transverse edge of the related side walls 3,4 so that the same will be spaced apart by the width of bottom wall 2 when said side walls 3,4 are in lowered, base-forming position (FIGS. 2 and 3).

Cooperating latch members 9,10 are mounted upon the portions of flanges 6,7, respectively, constituting top wall 1 for securing casing k in closed condition. A handle 11 is suitably mounted upon top wall 1 for facilitating transportability. Thus, in such closed condition as shown in FIG. 1 casing k constitutes a unique carrying case which requires minimum storage space.

For purposes of facilitating description of the present invention end wall 5 will be considered the forward end of apparatus A, that is, toward the right hand side of FIG. 5. Thus, as will be seen more fully hereinbelow the part of apparatus A nearest the operator will be deemed the forward side. Side wall flanges 6,7 are interconnected by a pair of toggle links 12,13; the former being pivoted at one end proximate the forward side terminal edge of flange 6 and the latter being pivotally mounted on an angle bracket 14 secured to side wall 4 and the adjacent portion of flange 7 (FIG. 7). The other end of link 12 is swingably secured as by a pin 15 to link 13 at a point spaced from its free end 13'. As will be seen in FIG. 8 the particular point of engagement between links 12,13 is substantially intermediate the width of bottom wall 2 so as to be located on the vertical centerline of apparatus A when in opened condition. The free end portion of link 13 embodies a forwardly extending lug 16 for overlying the proximate portion of the upper edge of link 12 when said links 12, 13 are in extended condition (as in FIG. 8) for resisting accidental upward swinging of link 12. Thus, links 12, 13 interconnect side walls 3,4 and the associated flanges to bring about joint or concurrent swinging action thereof as well as to tend to enhance the stability of apparatus A when in operative condition.

Mounted adjacent each end edge of bottom wall 2 is an angle shaped support bracket 17,17', the vertical flange of which is axially parallel with the adjacent end edge and against the inner faces thereof about the opposite ends of a flattened, relatively thick-walled tubular support bed 18 rigidly fixed on bottom wall 2 and extending lengthwise, along the longitudinal axis thereof. At its forward end, adjacent bracket 17, support bed 18 mounts the support structure c for ironing board b and at its other or rearward end, adjacent bracket 17', mounts iron raising and lowering mechanism f together with iron support linkage 1 (FIGS. 3 and 7).

Ironing board support structure c comprises a column 19 which may be of tubular stock, welded or otherwise secured at its lower end to support bed 18 and having a height less than the major dimension of side walls 3,4. Secured across the upper end of column 19 is the web 20 of a channel member 21 (FIG. 11) having upstanding side flanges 22,22' the planes of which are normal to the forward edge of apparatus A. Said flanges 22,22' at their outer ends provide bearings for a shaft 23 extending therebetween and projecting at its end beyond said flanges 22,22' for extension through aligned openings in the mounting ears 24,24'

of a connector component 25; which latter is thereby adapted for rockable movement about the axis of shaft 23. Said component 25 is of general U-shape having a web 26 which in its central portion is cut away as at 27 to permit clearance of web 20 when said component 25 is in rearwardly swung condition. At each of its ends, beyond the adjacent side portions of column 19, component web 20 is continuous with rearwardly turned portions 28,29 being presented laterally of the adjacent ears 24,24', respectively. Said side portion 28 is provided with a downwardly and rearwardly inclined edge 28' terminating in an upwardly opening hook 30 for purposes presently appearing. Suitably anchored to the inner face of side portion 28 is one end of a tension spring 31, the opposite end of which is secured to a boss 32 formed at the rearward end of flange 22' for thus urging component 25 into rearwardly swung position about the axis of shaft 23. Side portion 29 is articulated with its terminal portion, as at 29' being turned toward side portion 28 whereby said side portion 29 cooperates with the adjacent side flange 22' of member 21 to define a pocket p for purposes presently appearing; with the distance between terminal portion 29' and the proximate edge of web 20 constituting a mouth opening into said pocket p.

Pivoted on shaft 23 is the normally lower end of an ironing board support arm 33 preferably of tubular construction having a width slightly less than the distance between side flanges 22,22' so as to be receivable therebetween for purposes to be described. The opposite or normally upper end of support arm 33 is swingably mounted upon a shaft 34, the ends of which are journaled within openings provided in axially parallel, spaced-apart, longitudinal elements 35,35' of the support frame indicated generally 36 (FIG. 7) of the central section 37 of ironing board b; there being spacers 38,38' presented upon shaft 34 between elements 35,35' and support arm 33 (FIG. 14). It will be observed that shaft 34 extends transversely of said central section 37 being located rearwardly of the longitudinal axis of ironing board b.

Extending also between elements 35,35' and fixed at its ends therein immediately adjacent the rearward edge of central section 37 is a shaft 39 which intermediate its ends mounts the upper end of a link 40, the lower end of which is pivotally engaged upon a shaft 41 extending transversely through column 19 and being journaled at its ends in the walls thereof. Said link 40 extends immediately inwardly of side portion 28 of component 25 (see FIGS. 8 and 11) so that its lower end is located on the side of column 19 toward side wall 4. Shaft 41 is presented spacedly downwardly of channel member 21. Link 40 carries a laterally projecting pin 42 for reception within hook 30 of component 25 for ironing board stabilizing purposes as will be described hereinbelow. Upwardly of shaft 23 and downwardly of ironing board central section 37 support arm 33 carries a transversely extending shaft 43 axially parallel to shafts 23 and 34; said shaft 43 being suitably journaled in openings provided in support arms 33 for extension at its end therebeyond (FIG. 14). The end portion of said shaft 43 proximate side wall 4 carries the upper end of a lever 44 which extends downwardly and slightly laterally outwardly of side portion 28 of component 25 for pivotal connection at its

lower end, as by a pin 45 to the rearward end of a brace 46 which immediately forwardly of pin 45 is swingably mounted upon the projecting end of a shaft 47 extending transversely of column 19, being suitably journaled in openings formed in opposed portions of the wall thereof; said shaft 47 being proximate the lower end of column 19 and axially parallel to shaft 41 (FIG. 8). Said brace 46 is of general, downwardly opening U-shaped cross section and of such length so as to project forwardly and downwardly of column 19 when apparatus A is in operative position; there being a shoe 48 mounted on the forward end portion of said brace 46 for establishing firm engagement with the support surface. In its under portion, adjacent to, and forwardly of, its connection to shaft 47, brace 46 is cut away to develop an indentation 49 adapted for receiving the underlying edge portion of link 13 (FIG. 8) whereby when said links 12,13 are in extended condition said brace 46 serves to lock same against inadvertent swinging. Carried upon brace 46 between shaft 47 and pin 45 is an elongated cam 50 which is axially normal to the major axis of brace 46 and extends beyond the normally lower face of said brace 46, a distance sufficient to engage the lower edge of link 13, when extended, as brace 46 is swung into upward, inoperative position (see FIG. 9) for urging links 12,13 into upper non-extended condition for assisting in the movement of casing side walls 3,4 toward each other into closed condition. Carried upon link 13 is a guide pin 51 which projects from the rearward face of said link in upwardly spaced relationship to pin 15; said guide pin being receivable within an upwardly opening guide way 52 formed in a plate 53 secured upon the confronting portion of column 19 (FIGS. 8 and 9). Thus, said pin 51 serves to maintain links 12,13 when extended against any inadvertent horizontal displacement as well as any downward rocking. As shown in FIGS. 14,13, there is mounted at each end of shaft 43 the lower end of a strut 54,55 which at their other ends, are engaged to the frame portions indicated generally 56,57, respectively, of ironing board end sections 58,59, respectively. Each end section 58,59 is pivotally connected along adjacent transverse margins by hinges 60,61, respectively, whereby said end sections 58,59 are movable into coplanar relationship with central section 37 to present an ironing surface and with said sections 58,37,59 being of such dimensions that the same when extended are of like dimensions as a conventional ironing board. As will be shown, when ironing board b is in operative position, struts 54,55 will maintain the constituent sections in aligned condition. By means of hinges 60,61 said end sections 58,59 may be swung downwardly with respect to central section 37 through an angle of substantially 90° (see FIG. 2) for presenting said board b in contracted condition for storage.

Referring to FIGS. 12-14 inclusive it will be seen that each strut 54,55 is provided at its lower end with a bifurcated head 54',55' for effecting a swivel connection to said shaft 43. A similar head 62 is provided at the opposite end of strut 55 to allow for swivelling of such end. Strut 55 is of unitary rod construction, while strut 54 is of two-part character having a normally lower rod or male section 63 and an upper sleeve or female section 64 adapted to receive section 63; there being formed at the end of said section 63 within sleeve

64 an enlarged head 65 while the lower end of said sleeve is constricted as at 66 to prevent accidental loss of engagement between said sections 63,64. The upper end of sleeve 64 is suitably bifurcated as at 64' to provide a swivel-type engagement with a pin 67 fixed in frame portion 56. A tension spring 68 is connected at its ends to support arm 33 and rod section 63 of strut 54 for biasing same toward said arm 33 to enhance the supportive action of said strut 54. With special reference to FIG. 15 it will be seen that rod section 63 and sleeve 64, by virtue of their swivel connections at 54', 64', respectively, are adapted for mutual extension, said rod section 63 passing through an elongated slot 69 in sleeve 64 to allow of upward swinging of board end section 58 with respect to central section 37 for purposes presently appearing. Thus, by reason of the fixed length of strut 55 the related board end section 59 may not be upwardly swung. However, when end section 58 is in coplanar relationship with central section 37, head 65 will abut against the upper inner end of the bore of sleeve 64 in which state strut 54 is of like effective length as strut 55.

Each ironing board section 56,58,59 is fabricated preferably of a top sheet-forming section 70,71,72, respectively, as of suitable gauge metal with said sheets having rigidifying normally depending flanges. End section 58 is of general quadrilateral shape and is cut off at one corner along line 73 lying at an acute angle to the centerline of board b for developing a major portion 74 and a corner portion 75 having a relatively reduced marginal flange 76 so as to be of reduced thickness. Corner portion 75 is hinged to major portion 74 by an elongated straight hinge 77 extending along, and parallel to, the cut-off line 73. By means of said hinge 77 corner portion 72 may be swung into planarwise parallel, underlying relationship with respect to major portion 74 to develop a customary ironing board tapered end for facilitating the ironing of shirts, shirt collars, pants cuffs, shirt sleeves, and the like which may be easily slipped over or fitted upon the tapered portion. The relatively reduced thinness of corner portion 75 assures of its snug reception within the underzone of major portion 74.

To hold the folding corner portion 75 in either extended position as shown in FIGS. 3, 12, and 16, that is within the plane of ironing board b or in a folded position as indicated as being approached in FIG. 18 a latch mechanism generally indicated 78 is provided. This mechanism 78 comprises an elongated latch arm 79 pivotally mounted at its outer end to a mounting bracket 80 depending from the underface of corner portion 75 whereby said latch arm 79 will extend across hinge 77 with its other or free end as at 79' underlying major portion 74. Said free end 79' is slightly widened for effective engagement with a detent 81 extending downwardly from a mounting plate 82 secured to the underface of major portion 74. Detent 81 is vertically arcuated to provide a suitable keeper 83 for such widened free end 79' of latch arm 79. Engagement of latch arm 79 within keeper 83 is maintained through the normal gravitational bias of corner portion 75 since any downward tendency thereof urges latch arm 79 within keeper 83. Engaged about latch arm 79 proximate bracket 80 is a spring clamp 84 attached to corner portion 75 by means of an elongated flexible member

85 which inhibit free swinging of latch arm 79 about its pivotal mounting. Presented for effecting disengagement of latch arm 79 is a tripper 86 being of rod construction and having an operating finger 87 provided at its inner end, said finger being axially normal to latch arm 79 and disposed between same and corner portion 75. Substantially intermediate its links tripper 86 is turned at an angle of 90° to provide a mounting portion 88 journaled within a bearing 89 supported from the underside of corner portion 75. Beyond bearing 89, tripper 86 is continuous to a point immediately proximate the underside of the apex of corner portion 75 whereat it is bent into a handle-forming loop 90, the upper face of which bears against a leaf spring 91 suitably mounted upon the underside of corner portion 75 for normally urging said handle 90 downwardly, or away from the plane of corner portion 75 so as to concomitantly bias finger 87 toward corner portion 75 and hence away from latch arm 79. Thus, by pressing handle 90 against spring 91 so as to stress the latter tripper 86 will be rocked within its bearing 89 to cause finger 87 to be brought into forceful engagement with latch arm 79 to drive same away from corner portion 79 and urge from engagement with keeper 83. Thus, in order to free corner portion 75 for downward swinging with respect to major portion 74 handle 90 will be pressed against spring 91 with the operator simultaneously effecting a slight lifting movement of corner portion 75 for limited swinging about hinge 77 to cause latch arm 79 to lose engagement with detent 83 (see FIG. 17); the free swinging of latch arm 79 being limited by clamp 84 and member 85 as above described. Thereupon the user will swing corner portion 75 downwardly and thence upwardly toward the underside of major portion 74 as illustrated in FIG. 18 whereupon the free end of latch arm 79 will be received within an elongated slot 92 formed in the underside of major portion 74 and progressing therewith, for substantial reception, as corner portion 75 moves into planar parallel relationship to the underside of major portion 74. Clamp 84 and member 85 also assure of retention of latch arm 79 within slot 92. Provided in plate 82 is a socket 93 adapted to accept a pin 94, as of spring rod stock, fixed to a plate 95 rigid upon the underside of corner portion 75. Thus, when corner portion 75 is in full folded position beneath major portion 74 pin 94 having a slightly greater diameter than the cross section of socket 93 is forced into said socket 93 to assure of effective locking of corner portion 75 to major portion 74. Restoration of corner portion 75 to coplanar relationship with major portion 74 is easily effected by causing corner portion 75 to be swung downwardly and thence upwardly about hinge 77 to permit latch arm 79 to clear keeper 83 so that the same may be then re-engaged.

Ironing board *b* may be provided with a customary cover 96 with one end having conventional corner loops (not shown) for engaging the end corner portions of end section 58 and with the other end being drawn beneath end section 59 and being centrally secured to a tension spring 97 which is in turn tied to a draw-string 98; the inner end of which latter is passed through a guide bracket 99 provided on frame 56 for securement to strut 55 by means of a connector 100. Thus, it will be noted that when end section 59 is swung about hinge 61

into coplanar relationship with central section 37, cover 96 will be tensioned by means of drawstring 98 and spring 97 for maintaining cover 96 in snug engagement upon board *b*.

- 5 In view of the foregoing it will be seen that ironing board *b* is adapted by means of novel support structure *c* for movement into operative or expanded position (FIGS. 3 and 5) wherein the major portion of board *b* is disposed forwardly of the opened casing *k* whereby a user in seated position as upon a chair *s*, may dispose one's legs beneath board *b* so as to comfortably address iron *d* to the work; and said board *b* is equally easily moved into contracted or inoperative position (FIG. 2) wherein central section 37 will be in planarwise parallel disposition to bottom wall 2 and with end sections 58,59 being downwardly swung into substantially vertical position so that the casing *k* may be closed. It will thus be noted that the dimension of central section 37 relative to bottom wall 2 is such as to allow end sections 58,59 to be encompassed within a volume projected from bottom wall 2.

From the foregoing the actual operation of support structure *c* should be apparent; it being observed that upon opening of casing *k* said support structure *c* is initially operated to present board *b* in expanded position prior to manipulating the support linkage *l* for iron *d* and that upon termination of use of ironing apparatus *A* support structure *c* is operated to return board *b* to collapsed or inoperative position subsequent to corresponding manipulating of support linkage *l* and immediately prior to casing closing. With ironing board *b* in contracted condition as shown in FIG. 2 the user will lightly grip the forward side edges of end sections 58,59 and lift same laterally outwardly while pulling forwardly, which movement causes support arm 33 to be swung upwardly and forwardly about shaft 23 which thus raises board *b* spacedly above the upper end of column 19 (FIG. 3) while carrying same forwardly. As board end sections 58,59 are swung laterally struts 54,55 will swivel about their respective ends for accommodating such extended movement of the related end sections; it being noted that shaft 43 is traveling with support arm 33 and thereby limited in its rotative movement through the operation of lever 44 and brace 46 so as to assure stabilization of struts 54,55 in board-supporting disposition. Thus, as shaft 43 is moved upwardly with support arm 33 an upward pulling will be effected upon lever 44 which is carried therewith and the latter in turn will cause an upward swinging of the rearward end of brace 46 about its shaft 47 into position shown in FIG. 7 wherein brace 46 will be inclined downwardly and forwardly to present shoe 48 in firm surface engagement and with indentation 49 lockingly engaging toggle link 13. The upward and forward travel of ironing board *b* will cause link 40 to swing also upwardly and forwardly about shaft 41 causing pin 42 to travel relatively along edge 28' until the same is received within hook 30 which engagement thus restricts further swinging of link 40 and secures same firmly so that further forward travel of board *b* is inhibited.

65 Thus, as presented for usage board *b* is stable, being resistant to unauthorized twisting, tilting, or other unsteadiness and is conveniently presented substantially beyond casing *k* for the comfort of the operator.

To return ironing board *b* to inoperative or collapsed condition a reverse movement is required in that the user will lightly grip the forward edges of end sections 58,59 and push rearwardly thereon to cause pin 42 to lose engagement with hook 30 for unlatching support structure *c* and thus permit support arm 33 to swing rearwardly and downwardly into substantially horizontal disposition thereby causing central section 37 to be brought into substantial planar parallel relationship to bottom wall 2. Such action will effect a downward pushing upon lever 44 which in turn will cause a downward swinging of brace 46 about its inner end so as to remove shoe 48 from engagement with the support surface and break the lock between brace indentation 49 and toggle link 13; said lever 44 and brace 46 thus swinging into position shown in FIG. 9 wherein said brace 46 is immediately adjacent the side face of column 19 and inwardly of bracket 17. By such action cam 50 will exert an upward pressure upon link 13 so as to initiate mutual swinging of said links 12, 13 as well as assure against any inadvertent sticking of guide pin 51 within guide way 52. As central section 37 moves into lowered position end sections 58,59 will swing downwardly about their respective hinges, through gravity since struts 54,55 are freed for swiveling action to lie beneath central section 37.

Thus, the foregoing demonstrates the simplicity of support structure *c* for permitting facile movement of ironing board *b* between operative or expanded condition and contracted or stored condition; with the inherent co-action of components rendering said system easily manipulative by the average housewife without strain and while in a comfortable sitting position.

Iron *d* together with its support linkage *l* and the related raising and lowering mechanism *f* are supported upon a tubular upright 101 axially parallel to column 19 and being mounted upon bed 18 adjacent bracket 17' or at the rearward end of bed 18. Said upright 101 is relatively short and received within its upper end is the lower end of a mounting rod 102. Said rod at its upper end is engaged to the housing *h* which contains the raising and lowering mechanism identified as *f* hereinabove and which is of the type more fully described and set forth in U.S. Letters Pat. No. 3,496,659. The lower end of mounting rod 102 abuts a pin 102' extending transversely across the bore of upright 101 for maintaining said rod 102 in appropriate position.

The upper end of mounting rod 102 is integrally formed with a crank 103 having a horizontal section 104 axially normal to rod 102 and a vertical extension 105 formed at one end of horizontal section 104 for projection upwardly. The upper end of vertical extension 105 is engaged by a pin 106 to one end of a link 107, the other end of which is pivotally connected by pin 108 to the adjacent side wall 109 of housing *h*. Housing *h* is preferably formed of sheet metal material being of two-part construction having a movable cover plate, as indicated at 110 in FIG. 26, and a receptacle portion, as shown at 111 in FIG. 25, which latter comprises the aforesaid side wall 109 and a parallel side wall 112 with said side walls 109,112 being interconnected by a relatively wide end wall 113 in planarwise parallel relation to cover plate 110. Housing *h* is open at its lower end for receiving rod 102 and crank 103.

Horizontal section 104 of crank 103 is provided with a bore 114 for extension therethrough of a shaft 115 which is journaled at its ends within side arms 116,116' formed integral with a general H-shaped coupler 117. Coupler 117 comprises a substantially central web portion 118 having side arms 119,119' being opposed to side arms 116, 116', respectively, and adapted for journaling therein of a shaft 120 which projects beyond side arms 119,119' for engagement within openings (not shown) in side walls 109,112, respectively, of housing receptacle 111. It will be observed, (FIG. 26) that the outer end portions of shaft 120 are in axially parallel aligned relationship with pivot pin 108 of link 107. Formed with coupler 117 between side arms 116,116' is a mounting leg 121 to which is suitably connected the lower end of a spring link 122, said latter being in the form of a compact compression spring of the type more fully described in U.S. Re. Pat. No. 23,974. The upper end of spring link 122 is engaged about a mounting 123 fixed on a crank pin 124 carried upon a crank 125, which latter is mounted upon a drive shaft 126 projecting from a gear box 127 suitably fixed within housing *h*. Gear box 127 is operatively connected to a motor *m* which, when energized, effects rotation of shaft 126 at a predetermined angular velocity. Mounted on the side face of gear box 127 adjacent drive shaft 126 is a mounting plate 128 upon which is secured a pair of upper and lower microswitches 129,130 being located on opposite sides of shaft 126 for engagement by a cam 131 fixed on said drive shaft 126 for rotation therewith; said microswitches 129,130 each being normally urged into circuit closed condition, with alternate opening being effected upon engagement between cam 131 and the related microswitch 129,130, as the case may be. Each microswitch 129,130 is in circuit with motor *m*.

Secured to the underface of gear box 127 is an angle bracket 132, the vertical leg of which carries a mounting 133 to which is connected the upper end of a spring link 134, the lower end of said latter being engaged to mounting 135 provided on coupler 117. Said spring link 134 is of the same type as spring link 122 above described.

Mounted on the inner face of side wall 112 upwardly of gear box 127 is a U-shaped bracket 136 for supporting a shaft 137 having an end portion projecting through an opening (not shown) in side wall 112 for engagement thereon of one end of the main support arm 138 of the iron support linkage *l*. The outer end extremity of shaft 137 adjacent main support arm 138 is formed with an enlarged head 139 for engaging one end of an arcuate flat spring 140, the other end of which latter is secured by bolt 141 to said main support arm 138 spacedly from shaft 137 (FIG. 21).

Shaft 137 passes through a finger-like projection 142 of a latch plate 143 disposed between arm 138 and the side wall 112 of housing *h*. One side edge of said projection 142 constitutes a cam operating edge 144 which is continuous with a hook 145. The projection-remote end of latch plate 143 is provided with a normally forwardly extending lug 146 which is adapted to engage main support arm 138 when the latter is swingably rotated about shaft 137 in a direction indicated by an arrow in FIG. 20. Thus, in operation, when main support arm 138 is swung forwardly and upwardly, it engages lug 146 for carrying latch plate 143 upwardly

therewith until cam edge 144 engages a pin 147 fixed on the upper portion of housing side wall 112. Spring 140 absorbs the energy developed by the impact of the initial engagement of pin 147 and cam 144 so that arm 138 sustains minimal shock. Thereafter, detent 147 moves relatively along cam edge 144 as continued swinging of arm 138 is effected until restrained within hook 145, at which juncture support arm 138 will be in substantially vertical position (FIG. 20) and will remain upright by reason of the relationship between the hook 145 and pin 147 until such time as the operator forcibly urges lug 146 in a reverse direction for relatively removing pin 147 from within hook 145 for freeing main support arm 138 for return downward swinging.

Main support arm 138 is of general tubular construction having formed on its shaft-remote end a channel-forming receptacle 148 having a web 149 and a pair of side flanges 150,150' opening rearwardly toward bracket 17' when support arm 138 is in its downward position (FIGS. 7 and 22). Provided within channel flanges 150,150' proximate the end of web 149 is a pair of aligned openings 151,151', respectively, for bearingly supporting a shaft 152 extending transversely thereacross, and having enlarged heads 153,153' on each projecting end for retaining same in position. Engaged on shaft 152 is a pair of spaced-apart bearings 154,154' formed at the bifurcated end of a pivot arm 155, the opposite end of which is provided with an enlarged bearing 156 having a bore 157 in registration with aligned openings 158,158', respectively, formed within side walls 159,159' of a channel-shape mounting section 160 provided at the end of an intermediate support arm 161. Provided for extension through bore 157 and openings 158,158' is a pivot pin 162 having enlarged head portions 163, 163' for maintaining same in position within channel mounting section 160. It will be observed that said channel mounting section 160 is of less extent than the distance between flanges 150,150' of receptacle 148 so that the former may be received within the latter when said main support arm 138 and intermediate support arm 161 are in extended, operative relationship for iron support (FIG. 23) as will be presently described.

Formed integrally with bearing portion 156 is a projecting boss 164 having an opening 165 for receiving an externally threaded bolt 166 which is engaged within a turnbuckle 167 with its projecting end being connected to a cable 168 which serves as a flexible link. Thus, by rotation of turnbuckle 167 cable 168 may be loosened or tightened accordingly. Cable 168 is passed between bearings 154,154' of pivot arm 155 and into channel mounting section 160 for training around pulleys or sheaves 169,170, each of which is rotatively mounted on a pin 171,172, respectively, journaled within side walls 159,159'. Said cable 168 extends through a tubular portion 173 of intermediate arm 161 which tubular portion 173 is formed integral with the channel mounting section 160 and being continuous therewith.

The opposite end of intermediate arm 161 is connected through a conventional elbow joint 174 to a forearm 175 also being of tubular construction for extension therethrough of cable 168. The end of said forearm 175 remote from elbow joint 174 is provided with a socket member (not shown) for receiving a ball (not shown) which connects forearm 175 to iron *d* by

means of a pivot link 176, the lower end of which is suitably connected to the handle 177 of iron *d*. Thus, cable 168 at its outer end is suitably connected to the lower end portion of forearm 175 for operative purposes. Iron support linkage *l* is of the general type shown in U.S. Letters Pat. Nos. 3,251,147; 3,303,591; 2,939,229 and 3,137,953 for providing a floating suspension for iron *d*.

Iron *d* is of conventional type and may be either of dry or steam character and which is modified only to the extent of effecting engagement with pivot link 176 and the provision of an electric switch 178 (FIG. 28) operated by a hand lever 179 conveniently located on handle 177. Switch 178 is normally in circuit open position but when hand lever 179 is depressed switch 178 is moved into circuit closed condition for energizing motor *m* of iron raising and lowering mechanism *f* to lower iron *d* into engagement with the upper surface of ironing board *b*. When the hand lever 179 is released, iron *d* will be automatically raised, in a reverse manner.

Connected to said switch 178 is a plurality of conductors or leads 180 which progress from iron *d* through an opening 181 in forearm 175, interiorly of forearm 175, around elbow joint 174, through tubular portion 173 of intermediate support arm 161; thence through an opening 182 in side wall 159 of channel mounting section 160; then into an opening 183 in main support arm 138; and from the upper end of said pivot arm into housing *h* for ultimate connection to motor *m* of iron raising and lowering mechanism *f*. Motor *m* is in turn adapted for connection to a suitable wall outlet by a conventional cord 184.

Mounted on tubular portion 173 of intermediate support arm 161 on the confronting forearm 175 when said arm and forearm are in operative position is an outwardly opening receptacle 185 dimensioned for snuggly accepting the heel of iron *d* for storage of the same whereby handle 177 will be disposed in abutment against the adjacent portion of forearm 175 (FIG. 5) so as to prevent inadvertent displacement of iron *d* from its storage condition for it will be recognized that forearm 175 will be normally urged toward intermediate support arm 161 through bias of cable or tension link 168. The operation of iron linkage *l* may be best understood with reference to FIGS. 3 and 7 wherein the same is illustrated in stored or inoperative position and FIGS. 5 and 6 which show the linkage *l* in extended position for presenting iron *d* for use.

Thus with casing *k* in open condition and with ironing board *b* presented for use, as shown in FIGS. 3 and 7 and as described hereinabove, iron support linkage *l* is exposed for manipulation. It will be seen that in such contracted state, main support arm 138 is in downwardly swung condition, being axially parallel to upright 101 and on the side thereof proximate casing side wall 4 thus being disposed between bed 18 and the adjacent hinge. Intermediate support arm 161 is disposed for extension from the portion of bottom wall 2 beneath main support arm 138 upwardly, forwardly and across bottom wall 2 so as to dispose knuckle joint 174 slightly upwardly of side portion 29 of connector component 25 so as to present the proximate portion of forearm 175 within pocket *p* (see FIG. 11). Thus, forearm 175 will extend downwardly toward bottom wall 2 in immediate proximity, but rearwardly of,

column 19 with iron *d* being snugly received between forearm 175 and intermediate support arm 161 with the heel of iron *d* being engaged with receptacle 185. By reason of the novel connection between intermediate arm 161 and support arm 138, intermediate support arm 161 may be disposed in oblique fashion with respect to bottom wall 2 and with such position being stabilized by virtue of the engagement of forearm 175 within pocket *p*. Thus, when ironing board *b* is in contracted condition as shown in FIG. 2 iron linkage is completely obscured by the ironing board sections and thus received within the volume developed by the same with bottom wall 2.

With ironing board *b* in fully extended operative condition (FIG. 7) the user will grasp intermediate support arm 161 and pull same in a direction toward casing side wall 4 for removing forearm 175 from pocket *p*. At this point the user may swing ironing board end section 58 into upward position, as shown in FIG. 15, to provide ample clearance for manipulation of linkage *l* and with the return of said end section into operative position when such linkage has been moved rearwardly of board *b*. The swinging movement will be continued until linkage *l* is clear of the rearward edge of extended board *b* and then lifting force is applied so as to cause main support arm 138 to be swung into upward position (FIG. 20) and locked therein by reason of detent pin 147. Thereafter arm 161 is swung relative to main arm 138 for disposition upwardly thereof as shown in FIG. 23 wherein channel mounting section 160 is received within flanges 150,150' of channel-forming receptacle 148 and by reason of the eccentric disposition of pivot arm 155 channel mounting section 160 will tend to swing toward web 149 with such movement being delimited by abutment of boss 164 against detent 186 mounted in said web 149 (see FIGS. 22,23). Thus, with main support arm 138 stable and intermediate arm 161 being inhibited linkage *l* is in operative position with forearm 175 depending downwardly toward the upper surface of ironing board *b* and with iron *d* suspended therefrom after withdrawal from receptacle 185. It will be recognized that by reason of the disposition of mounting rod 102 within upright 101 linkage *l* may be readily pivoted about the axis passing through rod 102 so that the same together with housing *h* rotates freely for full maneuverability of iron *d*.

In order to effect ironing the operator will grip the iron handle 177 and press lever 179 for closing the circuit to energize motor *m* of the iron raising and lowering mechanism for lowering iron *d* which will be maintained in such lowered operating position as long as lever 179 maintains swing 178 in circuit closed condition. Upon release of pressure on lever 179 linkage *l* will immediately cause upward movement of iron *d* from board *b* for suspension while the operator arranges the work.

Upon energization of motor *m*, drive shaft 126 will be rotated with consequent rotation of crank 128 to cause the upper end of spring link 122 to be elevated and lowered. In elevated position (FIG. 25) spring link 122 will effect an upward rocking of coupler 117 about shaft 120 with consequent travel upwardly of rod 102 relatively within housing *h*; and when in lowered position, said spring link 122 will cause a downward pushing upon coupler 117 so that the latter will be rocked in

a counterclockwise direction with rod 102 being thereby lowered with respect to housing *h*.

Simultaneously with rotation of shaft 126, cam 144 will engage microswitch 129 upon upward movement of spring link 122 for effecting an opening of said microswitch 129 (FIG. 28). Upon further rotation of shaft 126, cam 144 will be caused to effect an opening of microswitch 130, thus allowing microswitch 129 through its normal bias to return to circuit closed condition.

Referring to FIG. 28, which illustrates the control circuit of the present invention, the iron heating element is shown diagrammatically at 187 with its temperature control at 188. Switch 178 is of the double pole type, having poles 189,190 with hand lever 179 being presented therebetween. Hand lever 179 is normally urged into circuit closing engagement with pole 189, through the bias of a spring (not shown) so that the circuit to pole 190 is normally open. Motor *m* and iron *d* are adapted to be energized from a conventional source of power, such as the usual household supply through conductor 185 plugged into the customary receptacle. One side of motor *m* is connected to power source *S*, and the other side connected in parallel relationship by conductor 191 to microswitches 129,130. Upon engagement of handle lever 179 so as to effect circuit closing engagement with pole 190, motor *m* is energized thereby effecting rotation of shaft 126 with consequent movement of cam 144 to cause circuit opening condition of microswitch 129 and microswitch 130 is thus returned to circuit closed condition. By such action, the iron *d* is lowered into operative position upon ironing board *b*. This condition will prevail until the operator releases hand lever 179 to effect circuit closure through pole 189 with consequent swinging of cam 144 through an 180° arc by reason of rotation of shaft 126 for restoration to the condition shown in FIG. 28 and with resultant elevation of iron *d*.

To return apparatus A to its compact, closed position, the operator must first place iron *d* within its receptacle 185 on intermediate support arm 138 and then pivot iron support linkage *l* about its vertical axis to a position rearwardly of ironing board *b*. Next the operator will elevate end section 58 about its hinge 60 in the manner above described, and release latch plate 143 from detent 147 thereby permitting downward swinging of main support arm 138, which thus allows intermediate support arm 161 to swing about pivot arm 155 to present channel portion 160 downwardly onto bottom wall 2 and immediately adjacent angle bracket 17' (see FIG. 7). The portion of forearm 175 immediately adjacent elbow 174 is then moved into pocket *p* of component 25 for maintaining linkage *l* in collapsed condition. Ironing board *b* is then moved into contracted condition as above described and the side walls 3,4 of casing *k* are then swung upwardly to permit of locking of same by latch members 9,10.

Thus, as above described apparatus A is an entirely self-contained unit which is easily operated by the average housewife. With references to FIGS. 1 and 2 it will be seen that the apparatus is so contrived that a user may position a chair adjacent the closed casing *k* as in the zone indicated 192 and which is laterally offset from the transverse centerline of casing *k*. While so disposed an individual may entirely open casing *k* and

effect expansion of apparatus A into full operative condition and in the same sitting position collapse said apparatus and close casing k.

Referring now to FIGS. 29-48 inclusive, A' designates another embodiment of the ironing apparatus of the present invention which unitarily comprises an ironing board b', a support structure therefor indicated broadly c', an iron d, support linkage for said iron indicated l', a raising and lowering mechanism f for said iron and a casing k' for receiving said components; it being observed that iron d and raising and lowering mechanism f are identical with the corresponding constituents of apparatus A above described while the remaining components are of fundamental like character as the corresponding components of apparatus A but with certain structural distinctions to be described for rendering apparatus A' more compact than apparatus A. By reference to FIGS. 31 and 34 it will be seen that when iron support linkage l' is in folded or collapsed condition iron d will be in substantially centered relationship to the storage area, that is, overlying the longitudinal centerline of bottom wall 2 of casing k' and thereby conducing to an even greater compactness than apparatus A wherein the axis of iron d as stored intersects longitudinal centerline of bottom wall 2.

Casing k' comprises top and bottom walls 1', 2', relatively wide side closure sections or walls 3', 4', and parallel end walls 5,5', with said closure sections 3', 4' being hinged to bottom wall 2' and with top wall 1' being latchable as with casing k above described. Closure section 4' is provided with a marginal flange 6 being the same as flange 6 as above described while closure section 3' is provided with a marginal flange 7' which, although of like depth of flange 7 above described, is cut away in its forward and rearward portions as at 200,201, respectively, for receiving cover plates 202,203, respectively, for completing the development of end walls 5,5' (see FIGS. 29,30), said cover plates being upstanding from bottom wall 2 and affixed to support structure c' and the base of linkage l' as more fully described hereinbelow.

Fixed on each end of bottom wall 2' are angle brackets 204, 204' and extending between same, the length of bottom wall 2' is a pair of parallel bars 205,205' being fixed on said bottom wall 2' and disposed immediately inwardly of the adjacent hinge; there being a transverse connector 206 extending between said bars 205,205' for enhancing the stability thereof. Thus, said bars 205,205' constitute a support bed for ironing board support structure c' and ironing board support linkage l'.

Secured, as by welding, to the forward end of each bar 205,205' is the lower end of an upstanding leg 207,207', respectively, said latter being in parallel relationship and terminating spacedly from casing top wall 1. At their upper ends legs 207,207', which if desired may be tubular, are rigid with the side flanges 208,208', respectively, of a cross member 209 the web 210 of which is presented spacedly forwardly of said legs as may best be seen in FIG. 38. Legs 207,207' are further rigidified by a channel shaped cross piece 211 secured thereon downwardly of cross member 209 (FIG. 36). Cover plate 202 is fixed to cross member 209 and is provided with lateral flanges as at 212,212' for secure-

ment to the side faces of legs 207, 207', respectively. Swingably mounted on each leg 207,207' at its upper end and on its inner face is the lower end of side pieces 213,214 of a swingable support arm 215; said side pieces 213,214 being relatively elongated and interconnected by upper and lower transverse members 216,217, respectively. At their other or normally upper ends side pieces 213,214 are engaged upon a shaft 218 journaled within openings provided in longitudinal elements 35,35' of the support frame 36 of the central section 37 of ironing board b'. *Encircling about shaft 218 is a torsion spring 219 having one end portion 220 directed rearwardly for engagement about a cross member 221 of support frame 36 and with the other end portion 222 being directed about upper transverse member 216 (FIGS. 44-46).*

Also extending between elements 35,35' and fixed at its end therein immediately adjacent the rearward edge of central section 37 is a shaft 39' which intermediate its end mounts the upper end of a stabilizer link 223; the lower end of which being pivotally secured to the inner face of leg 207, as by a pin 224, at a point immediately below cross piece 211. With reference to FIG. 38 it will be seen that the pivotal connection between side pieces 213,214 and legs 207,207' is eccentric so that in moving into operative position support arm 215 may swing forwardly but with the limit of such forward component of travel being determined by abutment against web 210. Thus, in full operative position support arm 215 will be inclined upwardly and forwardly for presentation of ironing board b' in desired extended position substantially forwardly of the proximate edge of casing k, for the same purpose and the same manner as ironing board b above described. Proximate lower transverse member 217 and normally immediately below same support arm 215 carries shaft 43 which projects at its end beyond side pieces 213,214 for swivelly engaging the normally lower ends of struts 54', 55 which are engaged at their opposite ends to frame portions 56,57 of ironing board end sections 58', 59'. Strut 55 and ironing board end section 59' are identical with the components identified by said reference numerals hereinabove, while strut 54' is substantially identical with strut 54 so that like portions will bear like numerals for the purpose of indicating the limited distinction. Similarly ironing board end section 58' is substantially identical with the corresponding ironing board end section above described but embodies a slightly different mounting for its corner portion as will be described below.

With reference now to FIG. 40 it will be seen that sleeve 64 is surrounded by a circular end portion 225 of a retention spring 226 which progresses along the exterior of sleeve 64 and thence through an elongated slot 227 formed within mounting pin 228, said latter being engaged within frame 56. Thus, spring 226 serves as a guide for maintaining sleeve 64 in proper disposition during raising and lowering movement of the related ironing board end section 58' and thus supplants spring 68 described above in conjunction with apparatus A. The ironing board central section 37 and end section 58', 59' mutually cooperate and function in like manner as the corresponding sections of ironing board b above described being movable into fully extended, operative position and returnable into contracted,

folded condition for snug reception into casing *k* when closed.

Shaft 43 proximate its connection to strut 54' carries the upper forwardly angulated end 229 of a lever 44' which extends downwardly, slightly laterally outwardly of leg 207 for pivotal connection at its lower end, as being pin 45' to the rearward end of a brace 46'; the same being substantially identical to brace 46 above described; said brace 46' being pivotally engaged, proximate, but forwardly of, pin 45', upon the projecting end of shaft 47' journaled at its ends, and extending transversely between, legs 207,207' (FIG. 36). At its normally forward end brace 46' mounts a shoe 48' and on its underface, just forwardly of shaft 47', is provided with an indentation 49' for lockingly abutting a shoulder 230 formed on the upper intermediate edge portion of an angulated control link 231 having a lower portion 232 pivotally engaged at its lower end extremity to the adjacent forward portion of flange 7' as by a pin 233; said link 231 having an upper portion 234 projecting through a suitable opening in the adjacent side portion of cover plate 202 for disposition forwardly of legs 207,207' and pivotal connection at its upper extremity as by a pin 235 to a slide block 236; which latter is disposed within a vertical slide way 237 formed in a slide plate 238 which is secured at its side edges to the forward margins of legs 207,207' and thus being within cover plate 202 (FIG. 36). Slide block 236 is engaged to the lower end of an extension spring 239 which at its upper end is anchored upon web 210. Symmetrically disposed with respect to control link 231 is a companion control link 240 having an upper portion 241 pivotally engaged as by a pin 242 at its upper extremity to slide block 236 which portion 241 projects through a suitable opening in the latter face of cover plate 202 toward closure section 4'; there being an intermediate normally downwardly extending portion 243 and a lower lateral portion 244 which is pivotally secured at its extremity to flange 6 of closure section 4'. It will be seen that the peculiar configuration of control links 231,240 permits of snug accommodation of the same within the spacing provided. It will thus be seen, as shown in FIG. 36, that with closure sections 3', 4' in open condition links 231,240 will be extended and with slide block 236 at the lower limit of its travel, spring 239 being under maximum stress. Said links 231, 240 are maintained against inadvertent movement under bias of spring 239 by reason of the abutment of brace 46' upon shoulder 230. Upon movement of ironing board *b*' into inoperative position, which movement is fundamentally of like character as above described in conjunction with ironing board *b*, with the consequent downward and rearward rocking of support arm 215, lever 44' will cause brace 46' to be swung upwardly, causing engagement to be lost between brace 46' and shoulder 230. In such condition closure sections 3', 4' are disposed for easy upward swinging toward each other in casing closed condition and with such movement being assisted by spring 239 which will urge slide block 236 upwardly into the position shown in FIG. 37. The movement of ironing board *b*' into operative position from fully contracted state is substantially facilitated by torsion spring 219 which serves as a counterbalance and on return movement of ironing board *b* from operative, extended condition to collapsed state

spring 219 also serves to materially assist such movement so that minimum effort need be exerted by the user.

Referring now to FIGS. 34,41,42,43, it will be seen that ironing board end section 58' is provided with a major portion 74' and a corner portion 75', which latter is of reduced thickness and hinged to major portion 74' by an elongated straight hinge 245. Said hinge 245 is constituted of a hinge rod 246 received within a normally downwardly and upwardly turned sleeve 247 integral with the central portion of the outer edge of major portion 74'; said rod 246 being fixed at its ends within bosses 248,248' presented in axial alignment with sleeve 247 and suitably secured, as by welding, to adjacent edge portions of major portion 74'. With reference to FIG. 41 it will be seen that sleeve 247 terminates at its ends spacedly from the proximate boss 248,248' to present exposed sections of said rod 246 as at 249,249'. Along its edge confronting sleeve 247, corner portion 75' is provided with a sleeve forming edge 250 through which extends a rod 251 projecting at its ends beyond sleeve 250 and being bent thereat for extension through companion sleeves 252,252' provided along the other margins of said corner portion 75'. Welded or otherwise fixed on rod 251 in the region of each bend is a boss 253,253' each of which mounts an annulus 254,254' for extension therethrough of the exposed sections 249,249' of rod 246 whereby said corner portion is swingable about said rod 246. Also provided upon each boss 253,253' laterally outwardly of the related annulus 254,254' is a detent 255,255', respectively, for seated disposition upon the shoulders *t* of an abutment 256,256' integral with bosses 248,248', respectively. Said shoulders *t* of each abutment 256,256' are planarwise parallel with the top surface of major portion 74' and is presented slightly downwardly of the longitudinal axis of rod 246 (FIG. 43). The exposed sections 249,249' of rod 246 are of such extent so as to allow relative shifting axially thereof by corner portion 75' with the limit of such movement being determined by the abutment of annuli 254,254' against bosses 248,248' and the confronting ends of sleeve 247.

Thus, in one position, as shown in FIG. 41, with detents 255,255' resting upon shoulders *t* corner portion 75' is coplanar with major portion 74' so that the entire surface of end section 58' is available for operation. By 50 slightly rocking major portion 75' upwardly to relieve the friction between detents 255,255' and shoulders *t* said corner portion 75' may then be shifted to bring annuli 254,254' in respective contact against sleeve 247 and boss 248', by which shifting detents 255,255' will be displaced with respect to shoulders *t*, for clearing same, thus permitting swinging of corner portion 75' either upwardly or downwardly and thence upwardly for disposition beneath major portion 74' to provide a desired taper to ironing board *b*'. In order to maintain corner portion 75' in underlying relationship to major portion 74', as illustrated in FIG. 42, the same is returningly shifted so that the opposite faces of detent 255,255' may be rested upon shoulders *t*', formed on abutments 256,256' in their inner portions, planar-wise parallel with related shoulders *t*. Extending upwardly from the ends of bars 205,205' proximate bracket 204' are relatively short legs 257,257' axially parallel to legs

207, 207', respectively, and being connected at their upper ends by a cross plate 258 planarwise parallel to bottom wall 2', said plate centrally carrying an upstanding socket-forming element 259 for receiving mounting rod 102 of raising and lowering mechanism f. Thus, legs 257, 257' and cross plate 258 constitute a support structure for said raising and lowering mechanism f as well as iron support linkage l' together with iron d. It will be observed that said legs 257, 257' and cross plate 258 define a forwardly opening volume v, for purposes presently appearing, which on its rearward side is determined by cover plate 203, said latter being suitably mounted upon said components.

Suitably fixed in each side wall of housing h adjacent the central portion of its upper end is a pin 260, each of which pivotally mounts a main support arm 261, 262 which are disposed on opposite sides of housing h being fabricated of tubular stock. Rigidly fixed to the opposite end portions of arms 261, 262 and extending therebetween is a transverse member 263 also of tubular stock; said transverse member 263 being presented for disposition against the rearward portions of said arms 261, 262 as determined when said arms are in upwardly swung position about pins 260, as shown in FIG. 47. Mounted upon transverse member 263 for presentation intermediate arms 261, 262 and axially parallel therewith is a forwardly and upwardly opening channel section 264 which is of substantially like character as the channel-forming receptacle 148 above described for receiving the normally lower end of intermediate support arm 161' which is structurally and functionally identical with support arm 161 above described and adapted for coaction with channel section 264 in the manner as said intermediate support arm 161 with channel-forming receptacle 148. The opposite end of intermediate support arm 161' is connected through a conventional elbow joint 174' to a forearm 175'; which latter, in turn, is connected to iron d, all as above described in conjunction with apparatus A.

In order to maintain iron support linkage l' in stable operative position there is provided a novel latch mechanism indicated generally M (see FIG. 47) which locks support arms 261, 262 in upwardly swung position with respect to housing h and being thus resistant to accidental collapse of linkage l'. Said mechanism M is of substantial symmetrical character incorporating a latch arm 265, the main plane of which is parallel to the adjacent side wall of housing h and being swingable mounted in one of its end portions on each pin 260, within the related support arm 261, 262 and having its opposite end portion extending through an opening 266 in the related support arm. Formed in the outer projecting end of each latch arm 265 is a hook 267 for presentation downwardly when said arms 261, 262 are in upwardly swung position. Proximate its engagement to the adjacent pin 260, but normally forwardly thereof, each latch plate 265 is contoured to present a shoulder 268 when said arms 261, 262 are upwardly swung and thus said shoulder being presented in the opposite direction as the related hook 267. When support arms 261, 262 are in downwardly swung or in apparatus-contracted condition (FIGS. 31, 34) latch plates 265 are free to swing downwardly about the associated pin 260 but with such swinging action being controlled by the length of the associated opening 266

so that said latch plate 265 is maintained against undesired displacement. Projecting laterally from each side wall 112, 109 of housing h proximate its upper rearward corner is a detent pin 269 for engagement with hook 267 of the proximate latch plate 265 when linkage l' is in operative condition. Thus, such engagement restricts any further swinging of the latch arms 265 and serves to render same stable in such position.

Engaging each shoulder 268 is the normally lower end of a rod 270 which extends within the associated support arm 261, 262 to approximately the upper end thereof whereat each rod 270 embodies an eyelet 271 through which extends pin 272 of relatively reduced diameter; said pins 272 being presented axially normal to the longitudinal axis of the related arm 261, 262 with the inner ends of said pins being free and the opposite ends extending through a slot-like opening 273 formed in the outer side wall of each support arm 261, 262. Fixedly mounted to the outer projecting end portion of each pin 272, as by a lug 274, is the normally forward end portion of the side arms 275 of a bail 276, the web 277 of which extends through transverse member 263 from end to end thereof. Accidental shifting of web 277 within transverse member 263 is prevented by virtue of end plugs 278 secured in each end of transverse member 263 and each having a groove 279 for accepting bail web 277. Formed integrally with bail web 277, substantially intermediate its length is a mounting pin 280 which projects through a slot-like opening 281 in the normally forward face of transverse member 263 into the space between arms 261, 262 a latch element 282 for locking relationship with a cooperative latch element 283 provided at the normally lower end of pivot arm 155' which latter corresponds with the related structure as shown in FIG. 48 is otherwise the same as the corresponding components of apparatus A above described. Said latch element 282 is of general L-shape having pawl edge 284 for engaging the tooth 285 constituting cooperative latch element 283. Formed integrally with one of said bail arms 275 and extending upwardly in the normally forward extremity thereof is a control lever 286 for facilitating unlocking operation of latch mechanism M as will be described.

Latch element 282 is urged upwardly at its outer pawl edge-bearing portion by means of a spring 287 which at one end is suitably fixed within the adjacent plug 278 and extends forwardly through an opening in arm 262 for engaging the proximate pin 272 for urging same upwardly within its associated opening 273 whereby lever 286 will be directed in maximum upward position. It will thus be seen that by applying pressure upon lever 286 to move same downwardly and forwardly from the position shown in FIG. 47, about arms 275 of bail 276 will be pulled downwardly causing web 277 to rock and thereby effect lowering of latch element 282.

From the foregoing the operation of linkage l' should be apparent. With the said linkage l' in collapsed or contracted condition as shown in FIG. 34, it will be seen that iron d is symmetrically disposed within the volume between support structure c' and raising and lowering mechanism f the same being by virtue of the symmetrical disposition of support arms 261, 262, legs 257, 257', support bars 205, 205' and ironing board support legs 207, 207' as the same delimit a storage zone. It

will be further observed that the normally lower end of intermediate support arm 161' is received within volume v by reason of the central disposition of channel section 264 between legs 257,257'. The end portion of forearm 175' forming part of joint 174' is received within a rearwardly opening channel bracket 288 (FIG. 38) fixed upon web 210 of cross member 209 adjacent the upper ends of legs 207,207'.

Iron linkage l' may be received from such stored condition, after ironing board b' has been extended in the following manner: the user will grip intermediate support arm 161' just above iron d and pull same rearwardly effecting a pivotal movement about the lower end of said support arm 161' so as to remove forearm 175' from bracket 288 whereupon said linkage l' may be pivoted about the axis of mounting rod 102 to permit forearm 175' to clear leg 207', then the user will pull upwardly on support arm 161' to permit the lower end thereof to clear bar 205' with continued pivotal movement of said linkage l' in a direction generally laterally overlying closure section 4' for appropriate avoidance of any interference with ironing board b'. Continued upward lifting is effected upon linkage l' causing support arms 261,262 to move into upright position with the same being determined by engagement of detent pin 269 within hook 270. With support arms 261,262 thus locked in upright condition (FIGS. 35,47) the user may release support arm 161' which through the gravitational pull of held iron d will tend to swing rearwardly about its lower end and with such movement being terminated by latching engagement of latch elements 282,283. In this condition intermediate support arm 161' is secured and iron d manipulated in the manner above described.

In order to return linkage l' to contracted condition the user will push rearwardly upon support arm 161' for lifting, as it were, the weight of the same from latch element 282 and then the user will pull forwardly and downwardly on lever 286 to overcome the bias of spring 287 whereupon bail 276 will be rocked so as to, firstly, effect unlocking between latch elements 282, 283 and, secondly, to force latch arms 265 downwardly at their forward ends through engagement between rods 270 and shoulder 268 for causing a lifting of hook 267 from pins 269 and thereby free support arms 261,262 for forward and downward swinging into lowered condition and thereby permit restoration of iron linkage l' to contracted condition.

Mounted upon the upper surface of transverse member 268 is a conventional, two prong electrical plug 289 suitably connected to a multi-lead conductor 290 for connection to motor m of raising and lowering mechanism f, there being conductors 290' to said iron. Thus, apparatus A' is readily adapted for connection to a convenient power outlet.

Having described our invention what we claim and desire to obtain by Letters Patent is:

1. An ironing apparatus for disposition upon a support surface comprising means defining a carrying case having a base wall and a pair of complementary closure sections, each of said sections incorporating a side panel portion hingedly engaged to said base wall along opposed margins for swingable movement of said sections toward each other into case-closed or carrying position and away from each other into case-opened

condition wherein said side panel portions are in coplanar alignment with said base wall upon the support surface, a multi-sectioned ironing board, an ironing board support fixed on said base wall having a height less than the height of said case and upstanding from said base wall, means interengaging said ironing board and said ironing board support for movement of said board between extended, operative condition when said case is opened, and collapsed, inoperative condition when said case is closed, an iron, a linkage support structure fixed on said base wall, an iron support linkage engaged to said iron, and means connecting said linkage support structure and said iron support linkage.

5 2. An ironing apparatus as defined in claim 1 and further characterized by said closure sections having marginal flanges cooperating to define end walls and a top wall of said case.

10 3. An ironing apparatus as defined in claim 1 and further characterized by said multi-sectioned ironing board comprising a central section and a pair of end sections, each of said end sections being hingedly engaged to said central section along opposed side margins whereby said end sections are swingable between planar aligned condition with said central section for presenting said board in operative condition and in planar normal condition thereto.

15 4. An ironing apparatus as defined in claim 3 and further characterized by said central section being of slightly less area than said case base wall whereby when said ironing board is in collapsed or inoperative condition said central section will be disposed in overlying, planar parallel relation to said base wall and said end sections will be downwardly swung therefrom into parallel relationship with the adjacent side panel portion of said closure sections.

20 5. An ironing apparatus as defined in claim 3 and further characterized by one of said ironing board end sections comprising a major portion and a three-sided corner portion, hinge means swingably mounting said corner portion on said related end sections, said hinge means being disposed along a hinge axis forming an acute angle with the longitudinal center line of ironing board, and means for securing said corner portion in selected disposition with respect to said major portion.

25 6. An ironing apparatus as defined in claim 5 and further characterized by said corner portion being shiftable along the hinge axis between same and the adjacent major portion, and inter-related means provided on said major portion and said corner portion for locking engagement when said corner portion is at one limit of its travel along said hinge axis.

30 7. An ironing apparatus as defined in claim 1 and further characterized by said means engaging said ironing board and said ironing board support comprising a swing arm mounted on the upper end portion of said ironing board support for movement between horizontal

35 disposition in overlying relationship to said base wall when said ironing board is in collapsed inoperative condition and upwardly swung condition wherein said arm extends above said ironing board support and projects endwise of said case whereby said ironing board will be presented upwardly and offset from the coplanar closure sections side panel portions but in planar parallel relationship to the support surface.

8. An ironing apparatus as defined in claim 7 and further characterized by a pair of struts pivotally carried on said swing arm, said struts being each swingably engaged in its portion remote from said swing arm to the adjacent end section of said ironing board.

9. An ironing apparatus as defined in claim 8 and further characterized wherein one of said struts comprises a rod, and means defining a sleeve for telescopically receiving said rod, means engaging one end of said sleeve to the related end section whereby said end section is rendered swingable in a direction normally upwardly of said central section through relative movement of said rod outwardly of said sleeve.

10. An ironing apparatus as defined in claim 9 and further characterized by said ironing board end section engaged to said sleeve means having a major portion and a three-sided corner portion, and hinge means interengaging said corner portion and major portion.

11. An ironing apparatus as defined in claim 7 and further characterized by means associated with said ironing board support for locking the swing arm in operative condition against accidental collapse.

12. An ironing apparatus as defined in claim 11 and further characterized by said locking means comprising a lever swingably connected at its upper end to said swing arm, a brace pivotally mounted on one side of said ironing board support, said lever being pivotally connected at its lower end to the proximate end of said brace, and means connected to said closure sections interengaging said brace when said ironing board is in extended operative condition.

13. An ironing apparatus as defined in claim 12 and further characterized by said means connected to said closure sections comprising toggle links.

14. An ironing apparatus as defined in claim 12 and further characterized by said means connecting said closure sections comprising a pair of control links, each link being engaged at one of its end portions to the adjacent closure section, a block slideably carried on said ironing board support for travel reciprocally vertically thereof, said control links being each engaged at its other end portion to said slide block, and resilient means urging said block upwardly.

15. An ironing apparatus as defined in claim 1 and further characterized by said means connecting said linkage support structure and said iron support linkage being an iron raising and lowering mechanism.

16. An ironing apparatus as defined in claim 15 and further characterized by said iron support linkage comprising at least one main support arm, an intermediate arm, and a forearm, said iron being carried at an end portion of said forearm remote from said intermediate arm, said main support arm being connected to said iron raising and lowering mechanism.

17. An ironing apparatus as defined in claim 15 and further characterized by said iron support linkage comprising a pair of main support arms disposed on opposite sides of said iron raising and lowering mechanism and being pivotally engaged thereon for swingable movement in a vertical plane, a transverse member extending between said main support arms in their end portions remote from their pivotal engagement upon said raising and lowering mechanism, intermediate support arm pivotally engaged at one of its ends to said transverse member intermediate said main

support arms, a forearm pivotally engaged at one of its ends to said intermediate support arm remote from its connection to said transverse member, and said iron being carried on the other end of said forearm.

18. An ironing apparatus as defined in claim 16 and further characterized by said main support arm being pivotally mounted upon said iron raising and lowering mechanism for swingable movement in a vertical plane between downwardly swung, inoperative position and upwardly swung operative position, the plane of swing of said support arm being above said base plate and within a projection of the area defined thereby, said intermediate support arm being hingedly engaged at one of its ends to the end of said main support arm remote from its pivotal mounting, said forearm being pivotally engaged at its end remote from the connection to the iron to the end of said intermediate support arm remote from its connection to said main support arm.

19. An ironing apparatus as defined in claim 16 and further characterized by a receptacle-forming member carried on said intermediate support arm for receiving the heel portion of the iron when the latter is not in use.

20. An ironing apparatus as defined in claim 16 and further characterized by latch means for maintaining said iron support linkage in iron supporting condition.

21. An ironing apparatus for disposition upon a support surface comprising means defining a carrying case having a base wall and a pair of complementary closure sections, each of said sections incorporating a side panel portion hingedly engaged along its normally lower edge to said base wall along opposed margins thereof for swingable movement of said sections toward edge other into case-closed or carrying position, and away from each other into case-open condition, in which last mentioned condition said side panel portions are in coplanar alignment with said base wall upon a support surface, each of said closure sections having end marginal flanges for cooperating to define opposed end walls when said case is closed, each of said closure sections having a top wall-forming flange at its upper margin for cooperating to define a case top wall upwardly of said base wall when said case is in closed condition, a multi-sectioned ironing board comprising a central section and a pair of end sections, said central section being of slightly less area than said case base wall, each of said end sections being hingedly engaged to said central section along opposed side margins thereof for swingable movement between planar aligned condition with said central section for presenting said board in operative condition and in downwardly swung condition in planar normal relationship to the side panel of the adjacent closure section

25 when said case is closed, an ironing board support fixed on said base wall and upstanding therefrom, a swing arm engaged to said ironing board beneath said central section, said swing arm being located upwardly of said base wall and being swingably engaged on the upper portion of said ironing board support for movement between horizontal disposition in overlying relationship to said base wall when said ironing board is in inoperative condition with said ironing board end sections being in downwardly swung position, an iron, a linkage support structure fixed on said base wall spacedly from said ironing board support, an iron support linkage engaged to said iron comprising a plurality of articulated

links mutually swingable, being compactly collapsible for reception between said ironing board end sections beneath said swing arm when said case is closed, and means connecting said linkage support structure and said iron support linkage.

22. An ironing apparatus as defined in claim 5 and further characterized by said means connecting said linkage support structure and said iron support linkage being an iron raising and lowering mechanism.
